UNITED STATES PATENT OFFICE.

WILLIAM E. BURROWS, OF ST. JOSEPH, MISSOURI.

VEHICLE-JACK.

1,389,737.

Specification of Letters Patent.

Patented Sept. 6, 1921.

Application filed April 3, 1920. Serial No. 371,046.

To all whom it may concern:

Be it known that I, WILLIAM E. BURROWS, a citizen of the United States, residing at St. Joseph, in the county of Buchanan 5 and State of Missouri, have invented certain new and useful Improvements in Vehicle-Jacks, of which the following is a specification, reference being had therein to the accompanying drawing.

10 My invention relates to improvements in that class of vehicle jacks which is used for lifting one corner of a vehicle, such as an automobile, a truck and the like; and the objects of my improvements are, first: to provide 15 a simple, substantial and efficient jack of this class by the use of which an object can be lifted to an extreme height by parts which can be moved to a position in which they occupy the minimum amount of space, 20 for transportation, packing and the like, second: to so construct and arrange the parts of a jack that they can be easily and quickly operated, and in which all of the movements of the parts are positive, thereby 25 avoiding accidents arising from disengagement of the parts, or slipping of the same, which frequently cause injury to the operator and damage to the vehicle being lifted by the jack, third: to so construct a jack of 30 this class, that it shall be extremely light of weight, neat in appearance, and be cheap in cost of manufacture.

I attain these objects by the mechanism illustrated in the accompanying drawings, 35 in which:

Figure 1 is a side view of the jack, showing the parts closed in normal position. Fig. 2 is a vertical section on the line 1 1, seen in Fig. 3, showing the parts of the jack 40 fully extended and a portion of the operating lever broken away. Fig. 3 is a horizontal section on the line 2 2, seen in Fig. 2, looking downward. Fig. 4 is a top view of the gear case cover, in detail. Fig. 5 is a 45 top view in detail of the cap of the jack. Fig. 6 is a horizontal section, on the line 3 3, seen in Fig. 2, looking downward. Fig. 7 is a section, similar to Fig. 6, on the line 4 4, looking downward.

50 Referring to Fig. 2, the cylindrically formed lower section 5, of the jack, is provided with a plurality of notches 6, which notches are formed in the lower end of said section. The screw thread 7, which is of 55 left formation, is formed on the inner sur-

face of said section, throughout its entire length.

Referring to Fig. 7, the holding lugs 8 are formed on the periphery of the holding disk 9, through the center of which disk the 60 square aperture 10 is formed. Said disk is placed in the lower end of said bottom section 5, with said lugs in the notches 6. The base 11 of the jack is provided with the shoulder 11' formed therein. Said base is 65 screwed onto said lower end of said section, tightly pressing said lugs in said notches, thereby holding said disk against rotation in said base.

A plurality of convolutions of the screw 70 thread 12 is formed on the lower end portion of the outer surface of the middle section 13, of the jack. Said thread is screwed between the convolutions of the thread 7, for raising said middle section from the position seen in 75 Fig. 1, to the position seen in Fig. 2, by rotation of said middle section in one direction, and vice versa for lowering said middle section. The screw thread 14, of right formation, is formed on the inner surface of the 80 middle section 13, throughout its entire length. A plurality of convolutions of the thread 15 are formed on the lower end portion of the outer surface of the upper section 16, of the jack, said thread being in engagement with the thread 14, for raising 85 said upper section from its lowered position, not shown, to the position seen in Fig. 2, by rotation of the middle section 13, in one direction and vice versa for lowering said upper section.

The jack cap 17 is provided with the externally screw threaded plug 18, formed on its lower surface, and with the raised checkers 19, formed on its upper surface, the latter being for the purpose of holding an object, resting thereon, from slipping therefrom. Said screw threaded plug is screwed into the internally threaded upper end portion of the upper section 16.

The gear case 20 has an opening 20' formed through its bottom, which is passed over the upper end of the middle section 16, after which the ratchet wheel 21 is secured on the upper end of said section, in any well known substantial manner, such as swaging the upper extremity of said section onto said wheel, welding or brazing.

The lower end portion of the pawl stud 22 is secured in the bottom of the gear case 110

20. The pawl 23 is oscillatably mounted on said stud. Said pawl is provided with the limbs 24 and 25, as seen in Fig. 3. The limb 24 is in engagement with the teeth of 5 the ratchet wheel 21, for rotation thereby in one direction, of said wheel. Said pawl and its integrally formed limbs are yieldably held in this position, by the spring 26, the free end of which presses against the face 10 27, which is formed on the outer portion of said pawl. The other end of said spring is secured on the inner surface of the adjacent end of said gear case.

The similarly formed pawl face 28 is shifted 15 into contact with the free end of said spring by moving the shifting stud 29 from the end of the slot 30, in which it is shown in Fig. 4, to the opposite end of said slot. This movement of said pawl moves the free 20 end of the limb 25 (see Fig. 3,) into engagement with said ratchet teeth, and moves the pawl limb 24 from its said engagement.

Said shifting stud is secured in the outer portion of said pawl and extends therefrom 25 through said slot, which slot is formed through the gear case cover 31, which is secured on the upper edge of the gear case 20.

Referring to Fig. 2, the apertures 31' and 20' are respectively formed through said 30 cover and gear case, the portions of which, bound said apertures are rotatably mounted on the hub 21' of the wheel 21.

Referring to Figs. 2 and 3, the bearings 32 are formed on the gear case 20, between 35 which bearings one buck-kneed end of the member 33, of the operating lever, is oscillatably mounted.

The other end of said member is buck-kneed connected with the lever member 34, 40 (see Fig. 2,) by the buck-knee connections 35.

The handle 36 (see Fig. 1,) is formed on the free end of the last mentioned member.

The squared end portion 37' of the holding rod 37 (see Fig. 2,) is inserted in the 45 aperture 10, in the holding disk 9, and is secured therein by the nut 38, which is screwed onto the threaded lower extremity of said rod. The spline keys 39 are secured in the upper end portion of said rod, and extend 50 therefrom into the spline channels 40, which are formed in the inner surface of the holding sleeve 41, for slidably splining said sleeve on said rod.

The upper end of said sleeve is similarly 55 provided with the spline keys 42, which extend therefrom, into the spline channels 43, which channels are formed in the inner surface of the upper jack section 16.

Said sleeve and rod, together with their 60 respective spline connections, form slidably splined holding means, whereby said upper section is held against rotation.

The shouldered termination of the lower 65 end of the spline channel 40 and the similar termination 43' of the spline channel 43,

limit the upward movement of the sleeve 41 and the section 16, thereby stopping further action of all of the parts of the jack.

The cap 17 is removed from the upper end of the last mentioned section, and a lubricant is poured into the thus opened upper end of said section, after which said cap is returned.

Said lubricant gravitates into and partially fills the lower section 5, for lubricating all of the screw threaded connections of the described sections and all of the previously described splining means. The lubricant reaches said parts, when they are lowered from the position seen in Fig. 2, 80 to the position seen in Fig. 1.

In actual practice it has been found, that the deflation of an extremely large pneumatic tire, lowers the axle of the vehicle on which it is used, to a point which is so close 85 to the ground, that the conventional jack can not be placed beneath said axle, and that where large tires of extremely great diameter are used the conventional jack can not be raised high enough to fill the requirements, hence the need of a jack of wide 90 scope in its action.

It will be understood that the size and proportions of the hereinbefore described parts are such, that said requirements are 95 thereby fulfilled.

In operation, with the parts in the position seen in Fig. 1, the operator of the jack grasps the handle 36 and thereby moves the lever members 33 and 34, from the position 100 seen in said figure to the position shown in Fig. 2, after which he places the cap 17 beneath the object to be thereby lifted.

He then draws said handle toward him, which by the described pawl and ratchet 105 mechanism, rotates the middle section 13, clockwise.

This movement of said section screws the same upward, by reason of its left screw threaded connection with the lower section 100 5.

While these movements are taking place, the previously described section holding means holds the upper section 16 against rotation, which section is also screwed upward, by its right screw threaded connection with the rotated middle section 13. This simultaneous upward movement of the sections 13 and 16 doubles the distance of 115 the movement of the cap 17, and the thereon supported object, when compared with the movement of the conventional two-section jack.

The operator thereafter moves said handle from him, thereby recovering the stroke 125 of said handle and the therewith connected pawl and ratchet movement. He then repeats said movements of said handle, until said object is lifted the desired height.

When desired, said object is lowered in 130

the following manner. Said operator moves the shifting stud 29 from the end of the slot 30, as seen in Fig. 4, to the opposite end of said slot, which moves the pawl 23, 5 thereby moving the end of the pawl limb 24, from its shown engagement with the teeth of the ratchet wheel 21. This movement of said pawl moves the free end of the pawl limb 25 into engagement with said 10 teeth, after which the spring 26 presses against the pawl face 28, thereby yieldably holding the end of the last mentioned pawl limb in its described engagement.

After this, the operator forces the handle 15 36 from him, which, by the last described pawl and ratchet mechanism, connected with said handle, rotates the middle section in the opposite direction, thereby lowering it and the thereby operated parts, including 20 the unshown previously described object. He thereafter draws said handle toward him for recovering the last described stroke of said handle, and then repeats these operations until said object is lowered as much 25 as desired. Further repeating of said lowering operations, moves the parts of the jack, from their described position, to the position shown in Fig. 1.

When it is desired to separate the parts 30 of the jack, the operator removes the cap 17 from the section 16, and removes the section 5 from the base 11, after which he removes the nut 38 from the rod 37. He now inverts said sections, after which, the sleeve 35 41 and the rod 37 gravitate therefrom. Said sections are thereafter separated by unscrewing their respective screw connections. By reversing these operations, the parts are again assembled.

Having fully described my invention, 40 what I claim as new and desire to secure by Letters Patent, is:

1. In a three-section jack; an upper section a middle section and a lower section 45 of tubular formation the last mentioned section having holding notches formed in its lower end said upper section having spline channels formed longitudinally in its inner surface, said upper section being telescoped 50 into said middle section while the last mentioned section is telescoped into said lower section; a base in which the lower end of said lower section is secured, said base having a shoulder formed therein; a disk having 55 a square aperture formed through the center thereof; a plurality of holding lugs formed on the periphery of said disk, said lugs being in said notches for holding said disk against rotation; a holding rod having a square portion formed thereon; rod securing means whereby said rod is secured on said disk with said square portion in said square aperture; a plurality of spline keys secured in the upper end portion of said rod extending therebeyond; a holding sleeve 60 having a like plurality of spline channels formed longitudinally in its inner surface, the extended portions of said keys being in said channels; and a plurality of other spline keys secured in the upper end portion of 65 said sleeve said other keys extending therefrom into the spline channels of said upper section of said jack; the whole forming slidably splined holding means whereby said upper section is held against rotation. 70

2. A vehicle jack comprising; a lower section; a base for said section; a middle section; an upper section; a checkered cap secured on the upper end of said upper section, said cap together with said jack being 75 adapted to be placed beneath an object to be lifted thereby; screw threaded connecting means whereby said sections are so connected that said middle and said upper sections are simultaneously raised by rotation 80 of said middle section in one direction and are lowered by opposite rotation thereof; slidably splined holding means in the center of said jack whereby said upper section is held against rotation; a ratchet wheel 85 secured on the upper end of said middle section; said wheel being provided with teeth formed on the periphery thereof; a hub formed on said ratchet wheel; a gear case; a cover for said case secured on the latter, 90 said cover and case being rotatably mounted on said hub; a reversible pawl oscillatably mounted in said case; a pair of pawl limbs formed with said pawl the free end of one of said limbs being in engagement with the 95 teeth of said ratchet wheel for rotating the latter in one direction; pawl oscillating means whereby said pawl is manually oscillated thereby so moving said case; and an extensible operating lever foldably hinged 100 on said gear case whereby said case and the therewith mounted pawl are manually oscillated for rotating said ratchet wheel and the therewith connected middle section in either direction. 105

In testimony whereof I affix my signature.
WILLIAM E. BURROWS.
